US00D540112S

(12) **United States Design Patent** (10) **Patent No.:** **US D540,112 S**
(45) **Date of Patent:** **** Apr. 10, 2007**

(54) **FOOTBALL-SHAPED BAKING CUP**

(75) Inventors: **Monica Stautner Nichols**, Richmond, VA (US); **Jennifer Danich O'Flynn**, Richmond, VA (US); **Michelle Shaw Johnson**, Glen Allen, VA (US); **Phillip L. Brookshire**, Cincinnati, OH (US)

(73) Assignee: **Alcoa Inc.**, Pittsburgh, PA (US)

(**) Term: **14 Years**

(21) Appl. No.: **29/258,671**

(22) Filed: **Apr. 26, 2006**

(51) LOC (8) Cl. **07-02**

(52) U.S. Cl. **D7/354**

(58) **Field of Classification Search** D7/323, D7/354, 356, 357, 359, 360, 409, 500, 552, D7/554.1, 554.2, 554.3, 554.4, 556, 586, D7/587, 601; D9/456; D15/90; 99/422, 425, 99/426, 428, 430, 432, 439-442, 444, 446, 99/DIG. 15; 206/557, 561-564; 220/405, 220/445, 447, 469, 500, 507, 508, 553, 555, 220/575, 626

(57) **CLAIM**

The ornamental design for a football-shaped baking cup, as shown.

DESCRIPTION

FIG. 1 is a top perspective view of the football-shaped baking cup, showing the present design;

FIG. 2 is a top plan view of the present design;

FIG. 3 is a bottom plan view of the present design;

FIG. 4 is a left elevation view of the present design;

FIG. 5 is a right elevation view of the present design;

FIG. 6 is a rear elevation view of the present design; and,

FIG. 7 is a front elevation view of the present design.
